BOOKKEEPING MACHINE

Russell G. Thompson, Rochester, N. Y., assignor
to Electromatic Typewriters, Inc., Rochester,
N. Y., a corporation of New York

Application April 24, 1931, Serial No. 532,539

12 Claims. (Cl. 235—59)

This invention relates to typewriting machines, and particularly to that class of typewriting machines known as bookkeeping machines. In such machines, the numerical keys are operatively connected with a computing mechanism so that the computing mechanism is operated each time a key is depressed to write a number.

The principal object of this invention is the provision of means for actuating the numerical type bars in such a machine to impress the platen with the same force as other keys which are independent of the computing mechanism, so that the numerals on the written sheet have a uniform appearance with other characters.

Another object of the invention is to provide power actuated mechanism for combined computing and typewriting machines which is of such a nature that there is no substantial difference between the load imposed on the source of power when numeral keys are depressed and both the computing mechanism and typewriting means are operated and the load imposed when a key other than a numeral key is depressed and only the typewriting mechanism is operated.

To these and other ends, the invention consists in the construction and arrangement of parts that will appear from the following description when read in conjunction with the accompanying drawing, the novel features being pointed out in the claims at the end of the specification.

Referring to the drawing, a cylindrical platen 1 is revolvably mounted in the frame of the machine, not shown herein. Pivoted in the frame are a plurality of type bars 2, only one of which is shown in the drawing. Mounted on each of the type bars are a plurality of types 3 adapted to engage the printing point on the platen when the type bar is actuated. Certain of the types may be adapted to print letters, and others, such as the type shown, are for printing numerical characters. The type bars are all pivoted on the usual curved pivot rod or wire 4. Each of the type bars is pivoted to a toggle lever at 5, having one arm 6 pivoted at 7 to the end of an arm 8 forming the other member of a toggle, the arm 8 being pivotally mounted on a common pivot curved rod 9. The other arm 10 of the toggle lever is connected to an arm of a bell crank lever 51 by means of a link 12. The bell crank lever 51 is mounted on the pivot rod 13 and has a forwardly projecting arm 52 provided with a laterally projecting stud or projection 53 at its forward end. Key controlled power actuated devices are provided for actuating the type bar. Said devices comprise

a key lever 53 mounted on a common pivot rod 54 and having a key 55 whereby it may be manually operated. The key lever has a downwardly projecting arm 56 which has a slot that engages a lateral projection on an arm of a lever 57 pivoted on an arm 58 of a bell crank pivoted at 59 in the frame of the machine. The arm 58 extends downwardly from its pivot 59 and has a cam 62 pivoted on its lower end adjacent the surface of a power driven roller 61. The latter rotates in a counterclockwise direction. The lever 57 has a downwardly projecting arm 63 having a stop 64 at its lower end arranged in the path of a lug 65 projecting from the cam. When the key lever is depressed, it swings the lever 57 and moves the stop 64 out of the path of the lug 65 when a spring-pressed arm 66 also pivoted on the arm 58 and engaging a projection 59' on the cam swings the cam into engagement with the power driven roller. When the stop 64 moves out of the path of the lug 65, it moves into the path of a second lug 67 on the cam and serves to arrest the cam after a one-half revolution, if the key lever be held depressed. When the key lever is released and returned to its normal position under the action of the spring 68, the stop 64 releases the lug 67 and the arm 66 engages a second projection 69 on the cam and turns it into engagement with the driven roller, and at the completion of a complete rotation the stop 64 again engages the lug 65.

The key lever 53 has an upwardly projecting arm 71 arranged on the pivot rod 54 and has a laterally projecting pin or stud 72 which engages a longitudinally arranged slot 73 in an interponent 14. The interponent is pivoted on the forward end of an arm 75 of the bell crank 13 pivoted at 59 and projects upwardly therefrom, and at its upper end has oppositely projecting fingers 16 and 11. It will be noted that the interponent 14 is substantially T-shaped in form, and that when the key lever 53 is depressed, it swings rearwardly from its pivot and engages its arm or finger 76 with the stud 59 on the arm 52, and at the same time the projecting arm 56 of the key lever swings the lever 57 to release the cam 62, which then becomes operative to swing the arm 75 downwardly and with it the interponent 14. By reason of the engagement of the arm 75 on the interponent 14 with the stud 59 on the arm 52, the bell crank is actuated to swing the type bar into engagement with the platen. This operation takes place during the first half of the rotation of the cam 62. When the key lever is released and re-

turns to its normal position under the action of the spring 88, the interponent is swung forwardly thereby from engagement with the stud 80 and into engagement with a stud 81 on one arm 82 of a bell crank lever 83, and the cam 62 is released to complete its revolution and again swings the arm 75 to actuate the interponent.

The bell crank 83 is pivoted on a common pivot rod 84 and has a downwardly projecting arm 85 having a lug 86 projecting into the path of the key lever 53 and limited in its forward movement when engaged with the lever by a lug 87 projecting downwardly from the lever. A link 88 connects the arm 82 of the bell crank with computing mechanism generally designated 96 in the drawing. A spring 95 connects the arm 82 with a fixed part and resiliently retains said arm in the normal position shown in the drawing and returns it to such position after each actuation by the interponent.

The computing mechanism is shown diagrammatically in the drawing, since the present invention does not relate to the specific construction of the computing mechanism and, as usual in combined typewriting and computing machines, the computing mechanism comprises totalizing or registering means and amount entering means. The totalizer and its amount entering means may be of the same type and construction as those described in Patent No. 873,314 granted December 10, 1907 to O. C. Kayle wherein the links attached to the numeral keys operate ratchet-and-pawl differential mechanism which enters amounts in totalizers seriatim through a master wheel. The links 88 can also operate some other form of conventional typewriter adding mechanism, for instance, links 88 could be the links 78 shown in Wahl Patent No. 1,270,471. These typewriter adding machines are now well known in the art and exist in several forms in commercial machines. It will be noted that in this embodiment, the totalizer is actuated positively and directly by the power operated devices, and that the spring 95 is operative to return the parts to normal position. It will also be noted that when the arm 82 is actuated to operate the totalizer, the lug 86 on the arm 85 moves into engagement with the key lever and holds it against a second operation until the spring 95 has operated to return the bell crank to normal position. By this arrangement, should the parts fail to operate properly for any cause, that fact would immediately be indicated to the operator when an attempt is made to again operate the key. It will also be noted that the type bar for writing numerals is actuated independently of the totalizer, so that there is no extra load on the power devices when a numeral type bar is actuated, which would cause a slowing up of said power devices resulting in a faint impression on the work sheet.

Although only one embodiment of the invention is shown and described herein, it will be understood that this application is intended to cover such changes or modifications as come within the spirit of the invention or scope of the following claims.

I claim:

1. In a bookkeeping machine, the combination of a platen, a type bar for writing numbers, a computing mechanism, power driven means for actuating said type bar and computing mechanism, a key lever, and means actuated by said key lever for operatively connecting said power

driven means with the type bar and disconnecting it from the computing mechanism.

2. In a bookkeeping machine, the combination of a platen, a type bar for writing numbers, a totalizer, power driven means for actuating said type bar and totalizer, a key lever, and means controlled by said key lever for operatively connecting said power driven means with the type bar when the key lever is depressed and with the totalizer when the key lever is released. 10

3. In a bookkeeping machine, the combination of a platen, a type bar for writing numbers, a computing mechanism, power driven means for actuating said type bar and computing mechanism, means movable to first operatively connect the power driven means with the type bar and then movable to operatively connect the power driven means with the computing mechanism, and a key lever for controlling both movements of said movable means and the operation of said power driven means. 15

4. In a bookkeeping machine, the combination of a platen, a type bar for writing numbers, a totalizer, power driven means for actuating said type bar and totalizer, an interponent operatively connected with said power driven means and alternately movable into operative engagement with the type bar or totalizer, and a key lever for moving said interponent and controlling the operation of said power driven means. 20

5. In a bookkeeping machine, the combination of a platen, a type bar for writing numbers, a totalizer, power driven means for actuating said type bar and totalizer, a bell crank operatively connected with said type bar, a second bell crank operatively connected with said totalizer, an interponent operatively connected with said power driven means, and a key lever for moving said interponent to and from operative engagement with said bell cranks and controlling the operation of said power driven means. 30

6. In a bookkeeping machine, the combination of a platen, a type bar for writing numbers, a totalizer, power driven means for actuating said type bar and totalizer, a bell crank operatively connected with said type bar, a second bell crank operatively connected with said totalizer, an interponent operatively connected with said power driven means, a key lever for moving said interponent to and from operative engagement with said bell cranks alternately and controlling said power driven means, and means on said second bell crank for locking the key lever against actuation when the totalizer is operated. 45

7. In a combined typewriting and computing machine, item recording means, computing mechanism, a power roller, a cam unit operatively engageable with the power roller, means to cause engagement of the cam unit with the power roller, and means operated by the cam unit for causing the item recording means and computing means to be operated separately in succession. 55

8. In combination, item recording means, computing means, power driven means for actuating both the recording means and computing means, means to initiate operation of the power means, means operated by the power driven means and controlled by the initiating means for successively connecting the item recording means and 70 the computing means to the power driven means whereby recording and computing operations are effected successively. 65

9. In combination, a recording element, a computing device, a power driven means for 75

actuating both said element and device, a key for initiating the operation of the power means, and means controlled by said key and actuated by said power driven means for operatively connecting the recording element and computing device to the power driven means in succession whereby recording and computing operations take place at different times.

10. In combination, recording means, computing means, power operated means for actuating both the recording means and computing means, an actuating device operated by the power operated means and movable to a position to operatively connect the recording means 15 to the power operated means and when restored causing the computing means to be connected to the power operated means; and selectively operable means for initiating operation of the power operated means, said initiating means having a 20 connection to the actuating device whereby operation of the initiating means first moves the actuating device to position to connect the recording means to the power operated means and then initiates operation of the latter, said initiating means when restored also first restoring

the actuating device to the position of connecting the computing means to the power operated means and thereafter initiates a second operation of the latter.

11. In combination a recording element, computing means, power-operated means for actuating both the recording element and computing means, an interponent connected to the power-operated means and alternately movable to positions to separately couple the recording element and computing means to the power-operated means, and a key for moving the interponent and initiating operation of the power operated means. 5

12. In combination, a recording device and a computing device, a pair of sub-levers each connected to one of said devices, a common operating member shiftable to engage said sub-levers alternately, power means to actuate said shiftable operating member and the sub-lever with 10 which said member is engaged, and means to shift the operating member and at the same time initiate operation of the power means. 15 20
